UNITED STATES PATENT OFFICE.

CHARLES A. SMYLIE, OF NEW YORK, N. Y., ASSIGNOR TO HIMSELF, THOMAS H. BAUCHE AND ADOLPHE E. SMYLIE, OF SAME PLACE.

DESIGN FOR A LICORICE STICK.

SPECIFICATION forming part of Design No. 31,389, dated August 15, 1899.

Application filed July 13, 1899. Serial No. 723,741. Term of patent 14 years.

To all whom it may concern:

Be it known that I, CHARLES A. SMYLIE, a citizen of the United States, residing in the borough of Manhattan, city, county, and State of New York, have invented and produced a new and original Design for Licorice Sticks, of which the following is a specification.

In the accompanying drawings, Figure 1 is a face view of a licorice stick embodying one form of my design. Fig. 2 is an edge view of Fig. 1.

A represents a licorice stick.

The leading or essential feature of my design consists of the panel a^2 , the rounded bulging or curved and rounded marginal portions a^3 , and the comparatively long and rounded or cylindrical portion a' . This latter is represented as divided into sections by

transverse grooves, and the marginal portions a^3 are also divided into transverse grooves, so as to be composed of protuberant portions a^4 .

It is apparent that this design is also applicable to confectionery-sticks other than licorice sticks.

Having thus described my invention, what I claim as new is—

The design for a licorice stick, substantially as shown and described.

In testimony whereof I have signed my name to this specification in the presence of two subscribing witnesses.

CHARLES A. SMYLIE.

Witnesses:

MYERS CURTISS,
LOUIS AUSTIN.
